Des. 208,806
Patented Oct. 3, 1967

208,806

ROTATABLE CANISTER UNIT

Beatrice Bliss, P.O. Box 47607,
Los Angeles, Calif. 90047

Filed Dec. 16, 1966, Ser. No. 5,071

Term of patent 14 years

(Cl. D44—6)

FIG. 1

FIG. 2

FIG. 3

FIG. 4

FIG. 5

FIG. 7

FIG. 6

FIG. 1 is a perspective view of a rotatable canister unit showing my new design;

FIG. 2 is an enlarged scale top plan view thereof;

FIG. 3 is an elevational view thereof;

FIG. 4 is a front elevational view of one of the canister members;

FIG. 5 is a left side elevational view thereof;

FIG. 6 is an elevational view taken from the left of FIG. 5; and

FIG. 7 is a bottom plan view of the canister member shown in FIG. 4.

I claim:

The ornamental design for a rotatable canister unit, substantially as shown.
